UNITED STATES PATENT OFFICE

JUSTUS F. NE PAGE, OF SEATTLE, WASHINGTON

CONCRETE POLE

Application filed April 7, 1927. Serial No. 181,728.

My invention relates to improvements in concrete poles in general and particularly to moulded concrete poles of artistic design, such as are used as ornamental street lighting

standards preferably as manufactured by the process specified and claimed in my co-pending application for U. S. patent, Serial Number 145,568, filed Nov. 1, 1926.

It is the practice to erect such lighting standards on the side walk and as near the edge of the curb as practicable in order to reduce the obstruction to pedestrian traffic to a minimum. In many instances, heretofore, vehicles having abnormally long hubs and other projecting parts have chipped and broken the surface of the concrete from the lighting standards. The gashes left in such cases are unsightly and detract from their otherwise pleasing appearance. This obvi-

ously is a serious objection to the use of lighting standards made of concretious materials in districts where the vehicular traffic is heavy; yet these districts are the ones where ornamental lighting standards are most used.

The principal object of my invention is to provide improved means for armoring concrete poles and the like against abrasions, chipping and surface breakage.

Another object is to provide a means of simplifying the manufacture of concrete lighting standards, poles, posts and the like.

A further object of the invention resides in providing means for the manufacture of ornamental street lighting standards that combine the desirable surface finish of cast metal with the strength, endurance and low cost of moulded concrete.

Other objects of the invention will be apparent from the following description and the accompanying drawings, and will be particularly pointed out in the annexed claims.

The drawings clearly illustrate a preferred embodiment of my invention in which:

Figure 1, is an elevation of the base portion of an armored concrete, ornamental street lighting standard with a mid-section of the supporting foundation.

Fig. 2, is a combined plan view with a cross section taken at line A—A, of Fig. 3, and is assumed to be rotated 45 degrees in

a counter clockwise direction from the position of the aforesaid elevation view.

Fig. 3, is a sectional elevation at line B—B.

Like reference numerals are used to indicate like parts throughout the drawings, in which 4 is an ornamental street lighting standard having a concrete body 5 reinforced by longitudinal steel rods 6 and a continuous steel spiral 7, both running the full length of the standard. The lower ends of rods 6 are hooked at 8 and engage holes in one end of angle anchoring lugs 9 as clearly shown in Fig. 3 of the drawings.

The lighting standard 4 is shown supported by a concrete foundation 10 of sufficient depth and base dimensions and in which bent foundation bolts 11 are cast in the usual manner with their threaded ends 12 projecting above the top of foundation 10 so as to pass through holes in anchoring lugs 9 provided for that purpose. The lighting standard is thus securely fastened to its foundation by means of said foundation bolts 11 and nuts 13.

The lower extremity of the base of the lighting standard is usually cast hollow, thus providing a space 14 in which electrical equipment, such as transformers, potheads and fuses, not shown, may be placed when required. A conduit pipe 15 is cast in the center of the lighting standard, to provide a raceway for the electrical conductors used to supply current to the lamps, not shown, mounted at or near the upper end of the 85 lighting standard.

Ready access to space 14 is had by removing a metal door 16, thus providing means for the installation or removal of the electrical equipment mentioned, and facilitating the making of electrical connections to the lighting mains and lamp leads, not shown.

A drain pipe 18 passing under lighting standard 4 and through the curb 19 at the outer edge of the side walk, is generally installed to serve as a drain for space 14 in order to guard against the accidental flooding of the electrical equipment.

The base portion of lamp standard 4 is protected against surface abrasion, chipping

and breakage by means of a metal casing or armor 17, which may be made of iron, steel, brass or other material, and may be cast or made in any other way that practical requirements may dictate.

It has been found desirable to extend the lower edge of the armor 17 below the surface of the sidewalk 19' in order to facilitate the erection of the lighting standard, and to provide a neat and workmanlike connection between the armor 17 and sloping sidewalk or other surface 19'.

Experience has shown the advantage of covering the projecting ends 12 of bolts 11 and nuts 13 with a little sand as indicated at 19" before pouring the surface concrete 19', thus enabling nuts 13 to be unscrewed readily in case it becomes necessary, for any reason, to remove the lighting standard.

Obviously the shape of the armor 17 may be made to conform to the artistic design desired, and is particularly applicable for busy thorofares where the traffic is often congested, and where the ornamentation for lighting standards of this type is more or less lavish. This is particularly true in cases where modifications of the Corinthian order of architecture are incorporated in the design, as heretofore it has been found necessary to make such designs with rather heavy proportions in order to be cast readily and successfully in concrete.

By means of my invention, however, the most elaborate designs may be readily cast or otherwise shaped in the metal armor 17, which is not subject to the limitations of concretious materials in this respect, and which provides ample strength to resist surface chipping and breakage.

It has been found desirable in some instances to enrich the appearance of the standard by making the base armor of brass or bronze which may be finished in natural tones of coloring thus producing a very rich appearance. In such cases it is found desirable to provide an exterior covering 20, preferably of the same or similar material, for the balance of the body of the concrete standard. This exterior covering 20 may be made from comparatively thin sheet material, and arranged to fit over the top of the main metal armor 17 by means of a simple slip joint as clearly indicated at 21 in Fig. 3, of the drawings. By means of this construction the completed standard has the appearance of being made entirely of bronze, yet possesses much greater strength.

It is apparent that the metal armor 17 and exterior covering 20 may be made comparatively thin as the metal is adequately supported throughout its length by means of the concrete, and need have only sufficient thickness to provide the necessary exterior finish and protection. For this reason, I find that such an ornamental street lighting standard

can be manufactured at a fraction of the cost required to make it entirely of brass or bronze, as has been the practice heretofore.

The method of armoring concrete poles, lighting standards and the like as herein described is found to be particularly applicable to the means and method of manufacture described in my co-pending application, Serial No. 145,568, filed in the U. S. Patent Office Nov. 1, 1926. I find that either the metal armor 17 or exterior cover 20, or both of them, may be readily mounted within the form together with the necessary steel reinforcing rods 6, steel spiral 7, anchoring lugs 9 and conduit pipe 15.

The mould is then mounted for rotation in a vertical position and the concretious mixture poured slowly into its upper end while the mould and armor are rotated at such speed as to form a paraboloidal basin 85 into which the suds from said mixture are squeezed by the settling and centrifuging of the heavier particles toward the periphery. The suds are finally spilled from the top by suitable means as the solids rise and the 90 mould is filled.

In this case, however, instead of shaping the mould to conform to the intricacies of the design, which has been necessary heretofore, I find that it is sufficient to provide a 95 snug fit for the high points of the ornaments and a good bearing for the main surfaces of the metal armor 17 and cover 20, thus greatly reducing the cost of the moulds.

Another saving effected in the manufacturing process by my invention is that the moulds may be stripped from the standard much sooner after pouring the concrete, because of the support afforded by the armor and cover which in themselves act as sufficient static forms for the concrete after the removal of the mould sections. Hence fewer moulds are required for the production of a given number of lighting standards; or a greater number may be manufactured in a 110 given time by means of a single form.

Obviously the metal armor 17 and shield 20 may be applied to existing poles or lighting standards by making the shield and armor slightly larger than the body of the 115 pole or standard and removing from said pole or standard such projections as the one indicated at 22 in the drawings. The concrete body 5 of the standard is then covered with a thin coating, preferably, of fine concrete or grouting and the metal armor and shield are forced into position one at a time under pressure, thus squeezing out the excess grouting and effectively filling the space between the surfaces of the body of the standard and the metal parts. I find that in this way I can apply my invention satisfactory to existing lighting standards without removing them from their foundations.

My invention is not necessarily limited to 130

the details of construction shown and described in the specification, as the invention may be employed in other forms that would suggest themselves to those skilled in the art, without departing from the spirit of the invention.

Having thus described my invention, what I claim is:

1. An ornamental lighting standard, comprising in combination, a reinforced concrete lighting standard of adequate strength for the normal requirements of the same, a relatively heavy metal casing or armor of artistic design adapted to encase and protect the sides of the base of said standard and extending upwardly to a point above the usual zone of traffic abrasion and an ornamental covering of relatively thin metal encasing the standard above said armor.
2. As an article of manufacture, a relatively long concrete lighting standard having an expanding base portion, reinforcing means embedded in the concrete forming said standard and cooperating therewith to afford adequate strength for the normal requirements of the same, an ornamental metal armor on said expanding base capable of withstanding ordinary surface abrasion, and an ornamental covering of relatively thin metal supported on the upper portion of said standard and having connection with the upper end of said base armor and cooperating with the base armor to present the appearance of an all metal standard.
3. The combination of a concrete lighting standard having an expanding base, reinforcing means embedded within said standard and coacting therewith to provide adequate strength for the normal requirements of the same, a metal armor of artistic design encasing the base portion of said standard, and a relatively thin metal covering encasing the upper portion of the same above said armor and cooperating therewith to present the appearance of an all metal standard.

The foregoing specification signed at Seattle, Wash., this 30th day of March, 1927.

JUSTUS F. NE PAGE.
